UNITED STATES PATENT OFFICE.

JACOB U. MANISCHEWITZ, OF CINCINNATI, OHIO.

ELECTRIC BAKE OVEN.

Application filed February 4, 1921. Serial No. 442,409.

To all whom it may concern:

Be it known that I, JACOB U. MANISCHEWITZ, a citizen of the United States of America, and resident of Cincinnati, in the county of Hamilton and State of Ohio, have invented new and useful Improvements in Electric Bake Ovens, of which the following is a specification.

My invention relates to an electrical method and apparatus for heating ovens in which are employed a plurality of electric heating elements; and the main object of my invention is to provide a method of heating electric heating elements whereby any desired temperature may be effected without loss of electric current, that is, all the electric current consumed is for heating purposes only.

Another object is to provide a simple system of wiring for the electric heating elements, eliminating the complicated and difficultly-accessible system now used.

I attain these objects by utilizing voltages of different electromotive force as herein-after fully described, and particularly pointed out in the claims.

Since electric heating elements are rated by wattage for their heating capacity, it is manifest from the following fundamental elementary electrical formulas: Amperes multiplied by volts equal watts, and watts divided by volts equal amperes, that, by keeping the amperage the same and varying the voltage, the resulting wattage is changed proportionately, and consequently temperature is similarly effected, without any loss of electric current or energy.

My invention, then, consists in an electrical method and apparatus for supplying or directing electric currents of different voltages to electric heating elements located within an oven chamber to effect different temperatures, and means, preferably exterior of the oven, adapted to direct said electric currents of different voltages to the electric heating elements.

The accompanying drawings form a part of this specification, and represent what applicant considers the best means for carrying out this invention. I do not limit myself, however, to the precise arrangement and details as herein disclosed, as other modes of applying the principle of my invention may be employed instead of the one explained, change being made as regards the arrangement and mechanism herein disclosed, pro-

vided the means stated by any of the following claims or the equivalent of such stated means be employed.

In the said annexed drawings Figure 1 is a side elevation of a stationary oven embodying my invention, showing electric heating elements at the bottom only; Fig. 2, a side elevation showing electric heating elements at both top and bottom of the oven chamber; Fig. 3, a side elevation (broken out between ends) of a traveling oven embodying my invention, showing electric heating elements below a movable member; Fig. 4, a side elevation (broken out between ends) showing electric heating elements both above and below a movable member; Fig. 5, a cross section of the oven taken at line A—B, of Fig. 1; Fig. 6, is a cross section of the stationary oven, but with electric heating elements at the top of the oven chamber; Fig. 7, is a cross section taken at line C—D, of Fig. 2; Fig. 8, is a cross section taken at line E—F, of Fig. 3; Fig. 9, is a cross section taken at line G—H, of Fig. 4; Fig. 10, a conventional diagram showing the main supply wires, the feed wires leading to the electric heating elements, and a switch means interposed between said main supply wires and said feed wires for directing electric currents of different voltages to said feed wires; Fig. 11, is an enlarged view of the knife switch forming a part of the switch illustrated in Fig. 10; Fig. 12, is a cross section of the knife switch taken at line I—J, of Fig. 11, further illustrating the positive and negative terminal construction; Fig. 13, a conventional diagram of the electric heating element employed in my improved oven; Fig. 14, a conventional diagram showing a method of wiring electric heating elements now in use.

Referring to the drawings, 1 denotes the chamber of an oven in which my method of electric temperature control and heating is incorporated, 2 and 3 are the side walls of the oven chamber, 4 the bottom wall and 5 the top wall. The front and rear oven chamber walls are denoted by the numerals 6 and 7 respectively. Numerals 8 and 9 denote suitable foundation side walls or footings and 10 and 11 denote suitable foundation end walls or footings. The construction of the walls 2, 3, 4, 5, 6 and 7 of the oven chamber is such as is necessary to prevent radiation of heat; and said walls generally are lined with metal or fire-brick, and prefer-

ably with a refractory material, denoted by 12, 13, 14, 15 and 16, but being of a suitable construction it is not specified in detail.

Electric heating elements 17, shown conventionally, and mounted in suitable frames 18, are mounted in the oven chamber 1, at the bottom, as shown in Figs. 1 and 3, or at the top, as shown in cross section at Fig. 6, or at both bottom and top, as shown at Figs. 10 2 and 4, but I do not limit myself to these locations of the electric heating elements. By my improved method, the degree of heat in all or any of the several electric heating elements 17 may be regulated to suit specific 15 needs, since a uniform electric current may be directed or supplied to the electric heating elements simultaneously, but of different voltages.

With some systems now in use that are 20 known to applicant several electric heating elements are wired together in series and series parallel and arranged to be "thrown in" in varying quantities to effect the degree of temperature required. With 25 this method, complicated wiring is necessary, and very inaccessible; further, temperature control is effected only by reducing or increasing the number of electric heating elements "thrown in," and for low temperatures many of the electric heating elements will be "cut out" altogether, resulting 30 in uneven distribution of heat, besides being detrimental to the electric heating elements that are in use. Fig. 14 shows a 35 form of wiring for electric heating elements, and is described more fully later on. Fig. 13 shows a conventional diagram of an electric heating element, the temperature of which is effected by directing electric current of different voltage to said electric heating element by means of the switch means 26, specified later. In other methods, the electric heating elements are slidably 40 mounted so that their proximity to the goods being baked may be regulated to effect the desired temperature, resulting in a great loss of electric current and hence very 45 inefficient.

Main supply electric wire conduits 19 and 50 20 are shown conveying the several main supply wires 21, 22, 23, 24, and 25 of different voltages, leading from a main source of supply. Switch means 26, of any suitable construction, and hence not shown in 55 detail, preferably located at the exterior of the oven, connect the main supply wires 21, 22, 23, 24 and 25 at terminals 27, 28, 29, 30, 31, 32, 33, 34, 35 and 36 by wires 37, 38, 39, 40 and 41 respectively. A swiveled 60 knife switch 42, or any other suitable means forming a part of the switch means 26, is arranged to be thrown in to any pair of the terminals, depending on what voltage 65 is to be directed to the electric heating elements 17. A positive contact 43 and a

negative contact 44, separated by an insulated member 47, are connected with the knife switch 42 by means of contacts 45 and 46 and cooperating members 55 and 56, which convey the current of predetermined 70 voltage to the feed wires 48 by means of the binding posts 49 and 50, and connect with the electric heating elements 17 at terminals 51 and 52, thereby completing the electric circuit. I have shown the switch 75 42 and cooperating parts as mounted upon an insulated member 53 forming a part of the switch means 26, and pivoted on stud 54, or any other suitable methods may be employed.

Assuming that a selected assortment of voltages such as 220, 165, 110, 82½, and 55, carried by the wires 21, 22, 23, 24 and 25 respectively, are the most desirable to effect a selection of temperatures, and that the greatest heat is necessary to "fire" the oven at the beginning of operations, the knife switch 42 is thrown in the terminals 27 and 28. As it becomes necessary to reduce the temperature, the knife switch 42 is pulled out of the terminals 27 and 28 and thrown in to either the terminals 29 and 30, 31 and 32, 33 and 34, or 35 and 36, as is necessary to effect the temperature desired. Line 48 carries the common wires to complete the circuit for the several main supply wires 21, 22, 23, 24 and 25, and said feed wires 48 partake of the same voltage as the main supply wires that said feed wires 48 are connected with by means of the knife switch 42. In the several drawings, the switch means 26, shown enclosed and mounted directly across the main supply wires 21, 22, 23, 24 and 25, embodies the entire switch mechanism, shown conventionally in Fig. 10, and connects to said main supply wires by the wires 37, 38, 39, 40 and 41, as shown in said Fig. 10.

The main supply wires 21, 22, 23, 24 and 25 are composed of two wires each—a positive wire and a negative wire. Also, the feed wire 48 is composed of two wires—a positive wire and a negative wire. So also, the supply wire 93, specified later, is composed of two wires—a positive wire and a negative wire. The positive wires are denoted by + and the negative wires by -.

Referring to the conventional outline shown in Fig. 13, it will be seen that the electric heating element 17 has but two terminals, the positive terminal 51 and the negative terminal 52, and but one set of feed wires 48 connecting these said terminals. For a comparison, applicant shows, in Fig. 14, a conventional layout of electric heating elements in which my method of directing different voltages into the electric heating elements is not incorporated. The electric heating elements 57, 58, 59, 60, 61, 62, 63, and 64, are connected by wires 65, 66 130

and 67 to any approved form of switch 68, and hence not shown in detail. For a "full" load, by turning the knob 92 to "full", appropriate contacts in the switch 68 connect the wires 65, 66 and 67 with main supply wires 93, and hence current is directed to all the electric heating elements 57, 58, 59, 60, 61, 62, 63 and 64. For a "medium" load, appropriate contacts in the switch 68 connect the wires 65 and 67 with main supply wires 93, and hence current is directed to electric heating elements 57, 58, 61 and 62 only, and electric heating elements 59, 60, 63 and 64 remain "dead" or "cut out". For a "low" load, appropriate contacts in the switch 68 connect the wires 65 and 66 with main supply wires 93, and hence electric current is directed to all the electric heating elements 57, 58, 59, 60, 61, 62, 63 and 64, but only one-fourth the electric current is carried by each said electric heating element because the said electric heating elements are thrown in series. It is manifest, therefore, by this method of wiring a plurality of electric heating elements and controlling them by a single switch means 68, if one of the electric heating elements burns out, while operating at other than a "full" load, there is an unbalanced or uneven distribution of heat; and, if two of the electric heating elements in a series parallel connection (as shown in Fig. 14) burn out, as electric heating elements 57 and 58, all the electric heating elements (57, 58, 59 and 60) connected in series parallel go out automatically.

It is sometimes desirable to place the articles on a movable member 69, instead of on a hearth-plate 70. The movable member 69 preferably is an endless carrier, and carries the articles through the baking chamber 1, through suitable openings 70 and 71 in the oven ends. In other types of ovens but one front opening 70 is required through which to place and remove the articles. The movable member or endless carrier 69 is rotatably mounted on suitable drums 72 and 73, and supported on members 74 suitably mounted in the oven chamber 1. Drums 72 and 73 are suitably mounted on shafts 87 and 76 respectively. Drum 73 may be driven by any suitable means, such as by means of a gear 75, suitably mounted on shaft 76, and a mating pinion 77, suitably mounted on shaft 78. On shaft 78 I have shown gear 79, which meshes with pinion 80, mounted on shaft 81 of a variable speed machine 82 of any suitable construction, and hence not specified in detail. Motive power is applied to the variable speed machine 82 by any suitable means, such as by means of a drive pulley 83, mounted on shaft 84, and drive belt 85, connected with any suitable source of main or prime motive power not shown in the drawings. Suitable bear-

ings 86 and 88 are provided for shafts 87, and 76 and 78. A discharge plate 89, at least the full width of the movable member 69, and secured in position by any suitable means, permits finished articles to slide off 70 the movable member 69 to any desired location.

For an oven of the traveling type it is desirable to vary the oven temperature at various positions of the oven length, chiefly 75 to overcome the fact that heat is carried along by the movable member. To the accomplishment of this and related ends I prefer to place the switch means 26 at several positions of the oven length, as 80 shown in Figs. 3 and 4, the number of said switch means 26 depending on the length of the oven and the kind of articles to be treated. The endless carrier 69 usually is returned through openings 90 and 91 in the 85 foundation end walls 10 and 11 respectively.

In the stationary types of ovens it also is advantageous to be able to control the several electric heating elements independently; or, a few of the electric heating elements may be connected (wired in parallel) to compose a unit, said unit having its independent switch means 26 adapted to direct different voltages to the electric heating elements to effect different temperatures. 95

I have not shown any outlets for the escape of vapors, gases or fumes, as these may be located in position appropriate to the articles being treated.

Having thus described my invention, 100 what I claim as new, and desire to secure by Letters Patent, is:

1. In an oven having an electrically heated chamber, electric heating elements in the chamber, a positive terminal and a negative terminal on each heating element, a multiple throw two pole switch for each heating element, an electrical connector connecting the terminals of the heating elements with the poles of the switch, a plurality of electrical main supply lines of different voltages, disposed without the oven, pairs of contacts about the switch for receiving the poles thereof, each pair of contacts being electrically connected with one of the main lines for selectively connecting an electrical current of a given voltage to a heating element. 110

2. In an oven the combination with a heating chamber, electrical heating elements 120 within the chamber, a two pole multiple throw switch for each heating element, a pair of lead wires connecting each heating element to the poles of one of the switches, a plurality of electrical main supply lines 125 of different voltages, pairs of contacts for receiving the poles of a switch, each pair of contacts having electrical connection with the positive and negative wires of one of the electrical main supply lines. 130

3. In an oven having an electrically heated chamber, an electric heating element in the chamber, a positive and a negative terminal on the heating element, a plurality 5 of electrical supply circuits carrying electricity of different voltages each circuit comprising a negative and positive line disposed exteriorly of the oven, and a multi-voltage switch for selectively connecting the 10 positive and negative terminal of the heating element with a positive and negative line of a supply circuit.
4. In a device of the class described the combination with an oven, of an electric heating element disposed in the oven, a plurality 15 of electrical main supply circuits car-
- rying electricity of different voltages disposed exteriorly of the oven, and a switching means for selectively connecting the heating element with the various main supply circuits for effecting different temperatures of the heating element within the oven. 20
5. In a device of the class described the combination with a heating element, of a plurality of electrical supply circuits of different voltages, and a switch for selectively connecting the heating element to any of the different circuits. 25

In testimony whereof, I have hereunto subscribed my name this 31st day of January, 1921. 30

JACOB U. MANISCHEWITZ.
